DESIGN FOR A PLAQUE

Gabriel P. Alvino, Newark, N. J.

Application December 24, 1941, Serial No. 104,831

Term of patent 3½ years

To all whom it may concern:

Be it known that I, Gabriel P. Alvino, a citizen of the United States of America, residing at Newark, in the county of Essex and State of New Jersey, have invented a new, original, and ornamental Design for a Plaque, of which the following is a specification, reference being had to the accompanying drawing, forming part thereof.

I claim:

The ornamental design for a plaque, as shown.

GABRIEL P. ALVINO.
